CLAIM

The ornamental design for a LED Light, as shown.

DESCRIPTION

FIG. 1 is a top perspective view of an LED Light showing our new design;

FIG. 2 is a left side elevational view thereof;

FIG. 3 is a front side elevational view thereof;

FIG. 4 is a back side elevational view thereof;

FIG. 5 is a right side elevational view thereof;

FIG. 6 is a top side elevational view thereof; and,

FIG. 7 is a bottom side elevational view thereof.

The broken line showing of the illuminated area is included for the purpose of illustrating the illuminated and forms no part of the claimed design.

1 Claim, 4 Drawing Sheets
